UNITED STATES PATENT OFFICE.

SYLVESTER LAWSON, OF KOKOMO, INDIANA.

LINE GUIDE.

Application filed May 5, 1921. Serial No. 467,053.

To all whom it may concern:

Be it known that I, SYLVESTER LAWSON, a citizen of the United States, residing at Kokomo, in the county of Howard and State 5 Indiana, have invented certain new and useful Improvements in Line Guides, of which the following is a specification.

This invention relates to line guides and the prime feature of the invention is the 10 provision of a guide whereby a single driver may control two sets of draft animals at the same time, especially when attached to riding breaking plows, the driver occupying the seat of the rear plow and driving a team 15 attached to an additional plow forwardly of the one upon which he is riding.

A further feature of the invention is in so constructing the guide mechanism that it may be attached to various makes of plows 20 and may be adjusted at various heights as occasion may require.

A further feature of the invention is the provision of adjustable rollers over which the lines from the forward team pass, said 25 rollers properly guiding the lines and causing them to have free movement lengthwise at all times.

Other objects and advantages will be hereinafter more fully set forth and pointed out 30 in the accompanying specification.

In the accompanying drawings,

Figure 1 is a perspective view of a plow showing the guide mechanism attached thereto,

Figure 2 is a rear elevation of the guide mechanism with the lower portion thereof broken away,

Figure 3 is an end elevation of the guide mechanism showing the manner of attaching the same to the seat portion of the plow,

Figure 4 is a front elevation of the upper portion of the guide mechanism, and

Figure 5 is a sectional view as seen on line 5-5, Figure 2.

Referring to the accompanying drawings, 1 indicates a plow structure which may be of any suitable make and known as a riding breaking plow, 2 indicates the beam portion 50 of the plow to which is attached the usual form of mold board 3 and to parts of the beam are connected a spring seat 4.

In order to enable a single driver to control two teams and two breaking plows at 55 the same time, one following the other, means is provided for guiding and supporting the

lines or reins attached to the forward team, and to readily accomplish this result a stand- 60 ard 5 is attached to parts of the beam 2 by extending a bolt 6 through the foot portion 7 of the standard while the vertical portion of the standard is held in rigid connection with the seat portion 4 through the medium of a bolt 8, one end of the bolt having a hook 9 which engages with parts of the seat 65 4, as best shown in Figure 3 of the drawings, the opposite end of the bolt extending through an elongated slot 10 in the standard 5 and having a nut 11 threaded thereon.

Co-operating with the standard 5 is a 70 shank 12 the upper end of which is bifurcated to receive a frame 13, said frame being preferably oblong. The lines or reins 15 employed for controlling the action of the team attached to the forward plow pass 75 through this frame, and in order to properly guide the lines, the frame has mounted therein vertical rollers 16 which are preferably arranged in pairs and between which the lines pass, as best shown in Figure 2 80 of the drawings, said rollers being mounted in the frame 13 in any suitable manner, but preferably by adjusting screws 17. The lines 15 also pass over horizontally arranged rollers 18, the forward edge of the frame 13 hav- 85 ing ears 19 projecting forwardly therefrom between which the rollers 18 are mounted, a bolt 20 passing lengthwise through the rollers 18, the ends of which are supported by adjusting screws 21. The rollers are pref- 90 erably separated by means of washers 14 on the bolt 20.

As the draft animals or teams are of different heights, the shank 12 is adjustably attached to the standard 5 by forming elongated slots 22 through the meeting ends of the standard and shank and through these slots is extended a locking bolt 23 for holding the shank in adjusted relation with the standard and the meeting faces of the shank 100 and standard are preferably provided with corrugations 24, as shown in Figure 5, these corrugations interlocking with each other and holding the frame 13 against lateral swinging movement when the shank and 105 standard are properly clamped together.

By passing the reins 15 through the frame 13 over the rollers 18 and between the pairs of rollers 16, the movement of said lines will be free lengthwise in whatever position 110 the draft animals may be to the driver on the rear plow and the movement of the ani-

2
mals attached to the forward plow may be readily controlled for guiding them or for turning when the end of the furrow has been reached without necessitating the driver 5 leaving his seat.

It will likewise be seen that by properly adjusting the guide frame, the lines for guiding the forward team need not encounter or interfere with the action of the team attached to the rear plow, as said lines will 10 pass over the heads of the animals attached to the rear plow.

It will likewise be seen that this device can be very cheaply manufactured and will 15 be practically indestructible from use as the various parts thereof may be readily adjusted to compensate for any wear.

Having thus fully described my said invention, what I claim as new and desire to 20 secure by Letters Patent, is:

1. The combination with a plow having a beam and a seat, of a line guide comprising a standard having an angularly extending foot at its lower end, means for attaching 25 said foot to parts of said beam, means for connecting said standard to said seat, a frame connected to the upper end of said standard, and guide rollers carried by said frame.

2. The combination with a plow having a beam and a seat, of a line guide comprising

a standard having a right angular foot at its lower end, a bolt for attaching said foot to the beam of said plow, a bolt for securing said standard to said seat, said standard having an elongated slot for the reception of said last bolt, a shank adjustably secured to the upper end of said standard, the upper end of said shank being bifurcated, a frame secured in said bifurcated end, and guide rollers carried by said frame. 35

3. In a line guide, a standard, a shank, a bolt for adjustably connecting said shank with the standard, said shank and standard having aligning elongated slots for the reception of said bolt, the meeting faces of said standard and shank having corrugations and the upper end of said shank being bifurcated, a frame carried by the bifurcated end of said shank, vertically and horizontally arranged 40 rollers carried by the frame for supporting and guiding lines passing through the frame, and screws engaging the ends of said rollers for adjusting them lengthwise. 45

In witness whereof, I have hereunto set 55 my hand and seal at Kokomo, Indiana, this 22nd day of April, A. D. nineteen hundred and twenty-one.

SYLVESTER LAWSON. [L. s.]
